(57) CLAIM

The ornamental design for a footwear, as shown and described.

DESCRIPTION

FIG. 1 is a top, rear and left side perspective view of a footwear, showing my new design;

FIG. 2 is a bottom, front and right side perspective view thereof;

FIG. 3 is a right side elevational view thereof;

FIG. 4 is a left side elevational view thereof;

FIG. 5 is a front elevational view thereof;

FIG. 6 is a rear elevational view thereof;

FIG. 7 is a top plan view thereof; and,

FIG. 8 is a bottom plan view thereof.

The dotted broken lines in the drawings illustrate stitches of the footwear that form no part of the claimed design. The broken lines in FIG. 7 illustrate portions of the footwear that form no part of the claimed design.
